DESIGN FOR A GAME BOARD

Howard E. Baack and Elmer A. Tischer, Chicago,
Ill., assignors to Frank Z. Woods, Chicago,
Illinois

Application May 1, 1935, Serial No. 56,652

Term of patent 14 years

To all whom it may concern:

Be it known that we, Howard E. Baack and Elmer A. Tischer, citizens of the United States, residing at Chicago, Illinois, have invented a new, original, and ornamental Design for a Game Board, of which the following is a specification, reference being had to the accompanying drawing, forming a part thereof. The design is of no appreciable thickness.

The figure is a plan view of a game board showing our new design.

We claim:

The ornamental design for a game board, as shown and described.

HOWARD E. BAACK.
ELMER A. TISCHER.
